UNITED STATES PATENT OFFICE.

ABRAHAM LIBERMAN, OF CLEVELAND, OHIO, ASSIGNOR OF ONE-FIFTH TO JAKE ROSEN, OF CLEVELAND, OHIO.

STOVE.

Application filed March 1, 1924. Serial No. 696,360.

To all whom it may concern:

Be it known that I, ABRAHAM LIBERMAN, a citizen of Poland, residing at Cleveland, in the county of Cuyahoga and State of 5 Ohio, have invented new and useful Improvements in Stoves, of which the following is a specification.

My present invention pertains to safety 10 appliances for stoves of the natural or manufactured gas type and it contemplates the provision of means whereby if through neglect or otherwise the flame from the burner should be casually extinguished the gas will travel to the chimney of the stove 15 and not back up through the gas outlets into the room or apartment.

The invention further contemplates the provision of means in use in connection with a gas stove whereby the direction of travel 20 of the flow of gas will be changed if the light at the burner is extinguished and the gas-cock remains open.

Other objects and advantageous features 25 will be fully understood from the following description and claims when the same are read in connection with the drawings accompanying and forming part of this invention; in which—

Figure 1 is a diagrammatic view of a 30 stove and showing my novel construction arranged therein.

Figure 2 is a transverse sectional view 35 showing the arrangement of my construction with respect to a stove.

Figure 3 is a view taken in the plane indicated by the line 3—3 of Figure 2 and looking in the direction of the arrows.

Figure 4 is a view showing in detail the 40 interior ring of the exterior burner ring and the vent from the ring.

Figure 5 is a sectional view taken in the plane indicated by the line 5—5 of Figure 3 and looking in the direction of the arrows.

Figure 6 is a top plan view of one of my 45 novel burner rings.

Similar numerals of reference designate corresponding parts in all the views of the drawings.

For the purpose of illustration, I show 50 the stove 1 having the burner plate 2 on which the supports 3 for the burner rings rest, and I also show the ordinary inlet pipe 4 having the well known cocks 5 and an open door 6 as illustrated together with the

pipe 7 and gas cock 8 for feed of gas to the oven.

Arranged to rest on the burner plate 2 immediately below the top of the stove and at the ordinary well known position are my 60 novel burner rings 9 that are by preference formed of an upper and lower semi-circular portions 10 and 11. I have designated the rings as a whole by 9 and the portions that go to make up the ring by 10 and 11 for the 65 sake of clearness and these sections are bolted or otherwise secured by means of the fastenings 12. The upper portion 11 is provided with the outlets 13 that are arranged off center for an important purpose herein- 70 after set forth and adapted to be encased by the upper and lower portions 10 and 11 of the ring 9 is a circular conduit 14 that is provided with the nibs or projections 15 that are conical shape as shown and are hol- 75 low throughout and the said nibs or projec- tions enter an aperture or opening in the conduit 14 and at the upper side thereof that in turn registers with apertures in the burner ring 9.

It will be noted that I provide feed pipes 16 from the inlet pipe 5 to the burner rings and it will be noted further that at the rear of the burner ring are three more or less nibs 17 that take into a conical member 85 18 before passing to the outlet pipes 19. Particular attention is directed to the fact that I construct the pipes 16 and 19 so that gas to and from the burner rings must take a tortuous course and this is done in order 90 to assist in baffling the return of the gas to the burner after leaving the burner which will be clearly set forth in the practical operation of the invention.

It will be further seen that some of the 95 burners are provided with outlet pipes 20 and these pipes are additionally bent as indicated by 21 so as to baffle the return of gas.

The pipes 19 and 20 eventually terminate 100 into and extend downwardly along the rear of a stove and rest in a chimney 22 that is provided at its lower end with a seal 23. This construction of seal is duplicated in the oven portion of the chimney as indicated by 105 23' and is open to permit the gas from pipe 50 to travel directly into the conical portion 24', by means of opening 29' and arranged in the chimney 22 are conical shaped members 24 and 24' open throughout 110

their lengths as indicated by 25', 26', 27' and 28' and communicating one with the other and at its lower end a draught aperture 25 is arranged in the chimney. Mounted on 5 the chimney 22 is a cap 26 that is arranged in the draught outlet 27 and has an upstanding tube 28 that terminates within the chimney 29.

The burners 9 may be constructed as illustrated in Figures 3 and 4 but I prefer that 10 they be provided with the central curved portion 30 as in Figure 6. The purpose of the curving, twisting and bending of the pipes of this improvement is in order to baffle, as much as possible, the return of unburned gas.

In the practical operation of the device, 15 gas enters the inlets 16 under pressure and goes into the interior 9^a of the rings 9 and is sucked through the nibs 15 and out of conduit 14 into the registering burner openings 13. If, however, the light of the burners 20 were accidentally extinguished, the nibs being directed at the angle disclosed and 25 staggered as shown would cause the gas to travel within the ring at 9^a until it reached the vent 18. The gas would then pass into the pipes 19 or 20 as the case may be and 30 from there into the chamber surrounding the conical shaped portions 24 of the chamber or chimney 22. The gas will strike the seal 23 and will travel around the conical portion 24 until it reaches the upper end of the conical portion when it will be forced by 35 air entering the lower end 25 of the chimney 22 into the tube 28 where it is carried off by the chimney 29.

In Figures 1 and 2 I have shown the oven 40 as equipped with my novel burner and the construction of this burner and its appurtenances is similar to that of the burners above referred to and it will be noted that the take off pipe 50 is provided with a kink 51 and the operation of this burner is similar to that of the ones before set forth.

It will be manifest from the foregoing 55 that if at any time through carelessness or otherwise the gas should become extinguished the liability of asphyxiation due to escaping gas is eliminated because of the fact that the gas cannot enter the room and pass through the openings 13 of the burners 9 if a burner is accidentally extinguished.

My invention is extremely simple in construction and arrangement and comprises 60 no delicate parts such as will become inoperative after a short period of use and in the future practice of the invention I do not care to be restricted to the exact construc-

tion of elements as set forth and illustrated 60 for the reason that I reserve to myself the right to make such changes and modifications as fairly fall within the scope of the claims appended.

Having described my invention, what I 65 claim and desire to secure by Letters Patent is:—

1. In means for the purpose set forth, the combination of a stove having a burner ring including a conduit; said ring having outlets therein, hollow nibs arranged in staggered relations within the conduit and having apertures that register with the outlets of the ring; said nibs being conical shaped in cross-section, a conical vent communicating with some of the nibs of the conduit, a chimney in direct communication with the vent and having a seal forming a chamber therein and also a draft passage whereby gas that enters the chamber will be forced 70 by draft through the passage.

2. A gas burner ring comprising a conduit, a gas inlet, projections arranged within the conduit and in communication with outlets formed in the burner ring, a vent 75 adapted to communicate with the interior of the burner, and means arranged in communication with the vent for precluding return of unburned gas to the burner ring.

3. In a safety appliance for gas burners, 80 the combination of a burner ring having a conduit and outlets arranged therein, nibs secured on the ring, a vent communicating with the interior of the burner and exterior of the nibs, a conduit communicating with 85 the vent and entering a chimney, a seal that provides a chamber in the chimney to confine the contents of the conduit and draft means for conducting the contents of the chamber into the draft pipe of a stove.

4. In a safety appliance for stoves and the like, the combination of a burner ring having outlets therein, a conduit in the burner, means for directing the flow of gas to the outlets to be ignited, said means being further 105 adapted to prevent the flow of gas that is not ignited to the outlets and means for carrying off the unburned gas comprising a chimney having a seal that produces a chamber and means for conducting gas from the 110 chamber.

In testimony whereof I have hereunto set my hand in presence of two subscribing witnesses.

ABRAHAM LIBERMAN.
